UNITED STATES PATENT OFFICE.

FREEBORN F. RAYMOND, 2d, OF NEWTON, MASSACHUSETTS.

NAIL-FEEDING IMPLEMENT.

SPECIFICATION forming part of Letters Patent No. 531,644, dated January 1, 1895.

Application filed May 2, 1890. Serial No. 350,314. (No model.)

To all whom it may concern:

Be it known that I, FREEBORN F. RAYMOND, 2d, a citizen of the United States, residing at Newton, in the county of Middlesex and State of Massachusetts, have invented a new and useful Improvement in Hand Nail-Feeding Implements, of which the following is a full, clear, and exact description, reference being had to the accompanying drawings, forming 10 a part of this specification, in explaining its nature.

The invention comprises a machine for feeding nails in gangs or groups to nail driving devices, and relates to various features 15 of organization and construction which are hereinafter described.

Referring to the drawings,—Figure 1 is a view principally in vertical section illustrating the features of my invention. Fig. 2 is a 20 view in rear elevation thereof. Fig. 3 is a view in plan. Fig. 4 is a view in plan of parts below the nail carrying wheel.

The invention is represented as contained 25 in an organization embracing a large rotary feed wheel having any desired number of pockets or holes in it, arranged preferably in circular order therein near the edge of the feed wheel, and of a size to receive the nails to be fed to the nail driving mechanism. This 30 feed wheel is rotatable upon a spindle or shaft to move any desired number of the holes into position to deliver a gang or group of nails to a distributer which connects such pockets or holes with the carrier of a nail driving device, or with the holes in the templet of a nail 35 driving device, or guide them to any other convenient point for use. There may be used in conjunction with this device a gang of drivers to push the nails from the holes of the feed wheel into or into and through the holes or passages of the distributer. The wheel is represented as rotated by hand, and as having a stop to latch it when any given number of holes have been moved into position over the 40 holes of the distributer.

Referring to the drawings, A is the frame 45 of the machine. It is of a form or shape to be placed upon a nail driving machine, and also to support or carry the nail distributer 50 a and the feed wheel B. The distributer a has the upper plate a' provided with the holes a² arranged therein upon an arc of a circle,

the lower plate a³ having the holes a⁴ arranged in the order in which the nails are to be driven or delivered, and preferably provided with a covering plate a⁵ adapted to be closed automatically by a spring a⁶, and to be opened by the nail carrier or other means, and the tubes a⁷ which extend into or through the holes a² of the upper plate into the holes a⁴ of the plate or block a³, and the holes of which form the passages through which the nails are fed, and by which they are guided to the form or arrangement in which they are to be driven.

b is a stud or post supported by the frame A, and which supports the feed wheel B. The feed wheel has the holes b' drilled therein near its outer edge in a circular line, and upon a circle of the same size as that shown by the arc of the holes a² in the plate a'. The holes are separated by a uniform space of the same extent as that which separates the holes a². It is represented as turned upon the stud b by the knobs or handles b². There is 65 below the plate a stationary hole-covering plate b³ which prevents the nails from dropping from the holes as the wheel is turned, and there is arranged upon the plate a' of the distributer a movable slide plate b⁴, which 70 is a continuation of the covering plate b³, and which acts to cover the holes a² and prevent the nails from dropping through the holes b' until it is desirable to permit the nails to drop or be delivered from the holes b' which 75 are in line with the holes a², to said holes and the passages of the distributer. This plate b⁴ is represented as moved in one direction by the lever b⁵ to uncover the holes b' and a², and as moved into position to close 80 said holes by the spring b⁶. When drivers are used, I extend the spindle b sufficiently 85 to form a support for a slide block C. This block receives or holds a driver block c in which is mounted any desired number of 90 drivers c'. These drivers preferably extend through the holes of a stationary templet or guide plate c² which holds them centrally in 95 relation to the holes b' of the feed roll and the holes a². The block c with the drivers is moved downward by hand or by power,—I have represented it by hand,—and is either moved upward by hand or by a spring c³, as 100 may be desired. The feed wheel has in its

100

edge notches d preferably opposite each hole, and there is attached to the frame a V-registering stop d' , which rides on the edge of the wheel and serves to hold or register the wheel 5 when its movement has been stopped to bring its holes into line with the holes a^2 of the distributor.

In use the mechanism is mounted upon the nail driving machine, the nails are fed to the 10 holes or pockets b' of the feed wheel by hand, the feed wheel being sufficiently large to permit two or three boys or attendants to feed nails to the holes at the same time, they sitting behind the machine and placing the nails 15 in the holes as the wheel is turned and as required. The wheel is turned preferably by one of the feeders to bring any desired number of its holes over the holes of the distributor. The slide b^4 is then moved to permit 20 the nails to drop through the holes of the distributor, and if desired the drivers or plungers c' reciprocate. For most uses drivers are not necessary. The nails fall through the passages of the distributor into the nail 25 carrier or nail templet, or other receptacle. In the drawings I have represented an automatic nail carrier which travels from the nail block to a position over a nail templet and beneath a gang of nail drivers, and 30 the nail carrier, which is lettered E, is provided with a pin e to come in contact with the slide plate covering the holes in the lower block of the distributor to open the same upon its backward movement and to permit 35 the nails to fall from the block into the holes of the carrier. After a group of nails has been delivered by the feed wheel, it is turned, another group of loaded pockets or holes brought into position to deliver its nails to 40 the distributor, and the holes from which nails have been previously delivered brought before the feeders to be filled.

Having thus fully described my invention, I claim and desire to secure by Letters Patent 45 of the United States—

1. In a nail feeding machine or device the combination of a nail distributor having the

entrances to its passages arranged upon an arc of a circle, with a large rotary feed wheel having holes or pockets upon the same circle 50 as the arc described by the upper ends of the passages of the distributor, and adapted to be rotated to bring gangs or groups of its pockets in regular order into line with the passages of the distributor, substantially as 55 described.

2. The combination of the distributor a , having its passages arranged as specified, the large feed wheel B having the holes b' , the plate b^3 beneath the wheel B, and the hole-covering and uncovering plate b^4 , substantially as described.

3. The combination of the distributor a , having its passages arranged on an arc of a circle the large feed roll B having the holes 65 b' , and a registering stop for registering the holes b' of the feed wheel with the holes a^2 of the distributor, substantially as described.

4. The combination of the distributor having its holes or passages arranged as specified, the feed wheel having the circular line of holes b' arranged in the arc of a circle and the reciprocating gang of drivers or plungers c' , also arranged in the arc of a circle substantially as described.

5. The combination of the distributor having the holes or passages a^2 , the slide plate b^4 mounted over the same, the lever b^5 for moving the plate in one direction, and a spring b^6 for moving it in a reverse direction, substantially as described.

6. In combination with a nail driving machine, a nail distributing device comprising a distributor a , having the entrances to its passages upon the arc of a circle, the rotatable feed wheel B having the nail holders or pockets b' adapted to deliver nails to the nail distributor as specified, all substantially as described.

FREEBORN F. RAYMOND, 2D.
